DESIGN FOR A DIAPER PANTEE OR SIMILAR ARTICLE

Tillie Goldstein, New York, N. Y.

Application September 21, 1940, Serial No. 95,274

Term of patent 7 years

To all whom it may concern:

Be it known that I, Tillie Goldstein, a citizen of the United States of America, residing in the city of New York, county of New York, and State of New York, have invented a new, original, and ornamental Design for a Diaper Pantee or Similar Article, of which the following is a specification, reference being had to the accompanying drawing, forming part thereof.

Fig. 1 is a front perspective view of a diaper pantee or similar article showing my new design.

Fig. 2 is a rear perspective view thereof.

Fig. 3 is a plan view of the diaper pantee or similar article in open position with the ties broken away for purpose of illustration.

I claim:

The ornamental design for a diaper pantee or similar article, substantially as shown.

TILLIE GOLDSTEIN.
